WINGTIP REFLECTOR FOR AIRCRAFT
AND THE LIKE

Farn T. Reed, 38474 Canyon Heights Drive,
Fremont, Calif.

Filed May 11, 1964, Ser. No. 79,904

Term of patent 3½ years

(Cl. D72—1)

FIGURE 1 is a side elevational view of a wingtip reflector for aircraft and the like, showing my new design;
FIGURE 2 is a front elevational view thereof;
FIGURE 3 is a rear elevational view thereof;
FIGURE 4 is a top plan view thereof; and
FIGURE 5 is a bottom plan view thereof.

The undisclosed side is the same in appearance as the side shown.

I claim:

The ornamental design for a wingtip reflector for aircraft and the like, substantially as shown and described.
